(57) **CLAIM**

The ornamental design for a footrest, as shown and described.

DESCRIPTION

FIG. 1 is a left front elevated perspective view of a footrest showing our new design.

FIG. 2 is a rear view of the footrest design of FIG. 1.

FIG. 3 is a front view of the footrest design of FIG. 1.

FIG. 4 is a right side view of the footrest design of FIG. 1.

FIG. 5 is a top view of the footrest design of FIG. 1.

FIG. 6 is a left side view of the footrest design of FIG. 1.

FIG. 7 is a left front elevated perspective view of a footrest showing a second embodiment of our new design.

FIG. 8 is a rear view of the footrest design of FIG. 7.

FIG. 9 is a front view of the footrest design of FIG. 7.

FIG. 10 is a right side view of the footrest design of FIG. 7.

FIG. 11 is a top view of the footrest design of FIG. 7.

FIG. 12 is a left side view of the footrest design of FIG. 7.

FIG. 13 is a left front elevated perspective view of a footrest showing a third embodiment of our new design.

FIG. 14 is a rear view of the footrest design of FIG. 13.

FIG. 15 is a front view of the footrest design of FIG. 13.

FIG. 16 is a right side view of the footrest design of FIG. 13.

FIG. 17 is a top view of the footrest design of FIG. 13.

FIG. 18 is a left side view of the footrest design of FIG. 13.

FIG. 19 is a left front elevated perspective view of a footrest showing a fourth embodiment of our new design.

FIG. 20 is a rear view of the footrest design of FIG. 19.

FIG. 21 is a right side view of the footrest design of FIG. 19.

FIG. 22 is a top view of the footrest design of FIG. 19; and, FIG. 23 is a left side view of the footrest design of FIG. 19.

The broken line showing is for illustrative purposes only and forms no part of the claimed design.
